NO. 11,232

JUNE 10, 1879

UNITED STATES PATENT OFFICE.

WALTER E. BANNING, OF SYRACUSE, NEW YORK.

DESIGN FOR SEAL-PRESSES.

Specification forming part of Design No. **11,232**, dated June 10, 1879; application filed May 8, 1879.
[Term of patent 3½ years.]

To all whom it may concern:

Be it known that I, WALTER E. BANNING, of the city of Syracuse, in the county of Onondaga, in the State of New York, have originated and designed a Pattern for Hand-Presses for Check-Protectors, Seals, and other Analogous Purposes, of which the following is a full, clear, and exact description, reference being had to the accompanying photographic illustration, making part of this specification.

A represents the base of the press; B, the platen or seat of the stationary die, and D the standard to which the actuating mechanism of the press is connected. This standard I make of a form representing in miniature a man in a sitting posture supporting at an elevation directly over the platen B a barrel or cask, C. The ears to which the press-lever is pivoted may be represented in the form of a

bag or sack lying upon the barrel, or of any other suitable device or object.

What I claim as my invention is—

A design for hand-presses for check-protectors, seals, and other analogous purposes, consisting of a miniature figure of a man in a sitting posture supporting at an elevation over the platen of the press a barrel or cask, substantially as shown and described.

In testimony whereof I have signed my name and affixed my seal in the presence of two attesting witnesses, at Syracuse, in the county of Onondaga and State of New York, this 3d day of May, 1879.

WALTER E. BANNING. [L. S.]

Witnesses:

CLARENCE BENDIXEN,
A. WOOD.
